(57) **CLAIM**

The ornamental design for a surgical procedure pack, as shown and described.

DESCRIPTION

FIG. 1 is a top view of a surgical procedure pack showing my new design;

FIG. 2 is a bottom view thereof;

FIG. 3 is a left side view thereof;

FIG. 4 is a right side view thereof;

FIG. 5 is a front side view thereof; and,

FIG. 6 is a rear side view thereof.

The evenly broken lines are shown for the purpose of illustrating wing features as well as tab border lines. The dot-dot-dash lines represent boundaries of the claim. None of the broken lines form part of the claim.
